ATTORNEY

UNITED STATES PATENT OFFICE.

JOHN WILLIAM EMSLEY, OF WORCESTER, MASSACHUSETTS.

LOOM.

SPECIFICATION forming part of Letters Patent No. 349,933, dated September 28, 1886.

Application filed March 27, 1886. Serial No. 196,752. (No model.)

To all whom it may concern:

Be it known that I, JOHN WILLIAM EMSLEY, a British subject, residing in the city and county of Worcester, State of Massachusetts, 5 have invented a new and useful Improvement in Looms, of which the following is a specification.

My invention relates to means for effecting the setting and adjustment of the lathes of 10 looms, as for leveling the "race" or other purposes, by raising or lowering either end by its swords or supporting-standards. Its nature is fully shown in the following description and accompanying drawings, illustrating 15 the application of my invention to one of said swords or standards.

In said drawings, Figure 1 is a side view showing the lower part of the sword of a lathe, the eye-socket, and bar connecting the two. 20 Fig. 2 is a central vertical section of the same. Fig. 3 shows a view of the end of the sword A as seen from below. Fig. 4 is a cross-section of the connecting-bar C on the line x y of Fig. 1.

The same letters indicate the same parts 25 wherever they occur.

A is the lower part or end of the sword or upright part supporting the lathe, made with a hole in the end to receive one end of the connecting-bar C, as shown in Fig. 2.

30 B is the eye socket or piece fitting on the "rocker-pin" in the usual manner, its upper part having a threaded hole, in which is fitted the screw on the lower end of the bar C, said bar C having its middle part made square, as 35 shown in section, Fig. 4, or otherwise provided with suitable means whereby it may be turned, and near its upper end having suitable beds or a groove, c, to receive the ends of one or more set-screws, as a a', to hold it when set or 40 adjusted, the beds being formed by holes or flattened places where wanted.

The operation in effecting the adjustment is evident: When the screws a a' are loosened, the bar C can be turned to raise or lower the sword A and the race it supports. Each end 45 of the lathe of the loom being similarly furnished gives full and complete control of the height of the race, and permits leveling it when desired. When duly adjusted, the screws a a' are tightened and hold the parts securely. 50

The bar C might be made with a square collar on its middle for turning it, or a round one with holes, if preferred.

Having thus fully described my invention, what I claim therein as new, and desire to 55 patent, is—

1. The combination of the eye-socket having the screw-threaded hole therein with the sword of a loom-lathe having a hole in the end thereof, the screw-threaded connecting-bar 60 C, and the set screw or screws a a', whereby the said bar is adjustably held at one end by its screw-thread and rigidly at the other by set-screws, substantially as described.

2. The adjusting-bar C, its middle portion 65 made square, whereby it can be readily turned, and having a groove or bed, c', in its upper end, combined with the sword A and the socket B, substantially in the manner and for the purposes described.

3. A sword and an eye-socket, combined 70 with a connecting-bar screw-threaded on its lower end and provided with a set-screw at the upper end, in the manner substantially as described, whereby at its lower end it can be vertically adjusted and at its upper end it can be rigidly held, and the sword thereby adjusted to and secured at any desired height. 75

JOHN WILLIAM EMSLEY.
